COMBINATION OF TRIM AND WALL
MEMBERS

William Franklin Parrish, Jr., and William F. Parrish, Sr., Indianapolis, Ind., assignors, by mesne assignments, to Ten Point Trim Corporation, Indianapolis, Ind., a corporation of Indiana

Application August 7, 1947, Serial No. 767,270

2 Claims. (Cl. 72—98)

1

This invention relates to a combined plaster ground and door trim to be used around wall openings, such as doors and windows in buildings. There are many advantages to be derived from the invention including the extreme simplicity of manufacture; the ease and rapidity of installation; the automatic securing of a closed joint between the strip embodying the ground and the door or window frame; and in the neat appearance as well as the presentation of a limited surface to be painted or otherwise finished.

These and many other objects and advantages will become apparent to those versed in the art in the following description of one particular form of the invention which is made in reference to the accompanying drawing in which

Fig. 1 is a view in perspective of a length of moulding embodying the invention;

Fig. 2, a view in side elevation of a fragmentary portion of the wall and frame to which the invention is applied, and

Fig. 3, a view in transverse section on the line 3—3 in Fig. 2.

Like characters of reference indicate like parts in the several views in the drawing.

The moulding generally designated by the numeral 10 is formed in desired lengths to have a planar foot 11 from which is outwardly turned a leg 12 also planar, this leg 12 being at right angles to the foot 11. From the outer portion of the leg 12 the material is bent around by a short bend 13 back and inwardly on the outside of the leg 12, Fig. 3, for a short distance which does not exceed to any great extent the thickness of the usual skim or white coat of the plaster.

Then from a line 14 defining the inward projection of the loop 13 on the outside of the leg 12, the material is carried laterally outwardly and then around in a continuous curving portion 15 to terminate by an end 16 which is spaced back or below the under side of the foot 11 a distance approximately around $\frac{1}{8}$ of an inch, this dimension being variable but sufficient to accomplish the desired purpose. In other words the arcuate portion 15 joins the outer portion of the leg 12, not directly, but only through the bend 13 which projects outwardly therefrom to serve as the actual edge over which the plaster is leveled by the usual float or other like tool. In reference to the extension of the bend 13 from the line 14, this of course may be varied but it is desirable to keep it at a minimum dimension such as around $\frac{1}{8}$ of an inch.

Defining the opening in a wall is the usual stud 17 against which a door or window frame

2

member 18 is secured either in direct contact as illustrated in the accompanying drawing, or separated therefrom by shims all in the usual and well known manner to those versed in the art. 5 In any event the frame member 18 is provided with a slot 19 extending longitudinally therealong, and importantly, having its side walls inclined outwardly from the entrance side 20 in respect to the back face 21 of the member 18, Fig. 3. The length of the moulding 10 is applied by inserting the end 16 into the slot 19 and bringing the foot 11 up flatly against the stud 17 as indicated in Fig. 3. The foot 11 is provided with a plurality of holes 22 therethrough to receive nails or the like 23 therethrough as they may be driven into the stud 17. It may be desirable also to supply holes 24 through the junction of the foot 11 with the leg 12 whereby nails 25 may be driven diagonally through the moulding 20 and into the stud 17, or primarily into the frame member 18 as indicated in order to fit the leg 11 snugly and compressibly against the stud 17.

Further the formation of the moulding 10 is such that when the foot 11 is brought into full contact with the stud 17, the end portion of the moulding 10 terminating in the end 16 is forced around into compressive contact with the outer corner 26 of the slot 19. This contact is initially made and maintained by reason of the curvature 30 of the moulding part 15 which causes the edge 16 to slide down the inner wall 27 of the slot 19 then to straighten slightly the portion 15 and thereby urge the outward convex surface against that corner 26.

35 Then in the usual manner, plaster board or lath 28 is nailed by an edge portion to the stud 17 such as by the nails 29, and the plaster 30 is applied thereover and leveled over the bend 13 with the skim cut 31 applied thereafter. Generally the thickness of the board 28 is $\frac{3}{8}$ " and the plaster 30 is of the same thickness to equal the overall dimension of the leg 12 from the foot 11 to the outside of the bend 13 to be substantially $\frac{3}{4}$ of an inch. The moulding 10 is provided with clinch holes 32 through the leg 12 whereby the plaster 30 may flow therethrough when it is applied and clinched over the leg 12 behind the portion 15. The concave portion 15 may be painted or otherwise finished as may be desired to give a very neat as well as a protective surface around the edge of the plaster, between it and the frame member 18.

While I have herein shown and described the invention in the one particular form, it is obvious that structural changes may be employed

without departing from the spirit of the invention and I therefore do not desire to be limited to that precise form beyond the limitations which may be imposed by the following claims.

I claim:

1. The combination with two juxtaposed wall structure members wherein a surface of each is approximately in a common plane, of a trim molding bridging said members; one of said members having a slot entering its said surface to extend longitudinally thereof; said slot being defined by spaced apart, substantially parallel walls inclined from said one member surface sloping therefrom within the member away from said second member, the slot wall farthest removed from said second member forming an acute angled corner between it and said surface; said trim molding having a foot bearing over said second member surface, and having an arcuate portion carried by said foot and extending laterally therefrom; said arcuate portion having an outwardly convexly curved length terminating in a free edge spaced laterally from said foot a distance bridging said two members between said edge and said foot; said edge being spaced back of said foot a distance entering within said slot below said one member surface with said foot bearing over said second member; the transverse width and the inclination of the walls of said slot and the curvature of said arcuate portion having that relationship wherein said curved length bears substantially by a line contact along said corner compressively urged thereagainst by said edge bearing compressively against the opposite slot wall from said corner.

2. The combination with two juxtaposed wall structure members wherein a surface of each is approximately in a common plane, of a trim molding bridging said members; one of said members having a slot entering its said surface to extend longitudinally thereof; said slot being de-

fined by spaced apart, substantially parallel walls inclined from said one member surface sloping therefrom within the member away from said second member, the slot wall farthest removed from said second member forming an acute angled corner between it and said surface; said trim molding having a foot bearing over said second member surface, and having an arcuate portion carried by said foot and extending laterally therefrom; said arcuate portion having an outwardly convexly curved length terminating in a free edge spaced laterally from said foot a distance bridging said two members between said edge and said foot; said edge being spaced back of said foot a distance entering within said slot below said one member surface with said foot bearing over said second member; the relationship of the transverse width, the inclination of the walls of said slot, and the curvature of said arcuate portion having said curved length of the arcuate portion bearing substantially by a line contact spaced from said edge and along said corner under a straightening bending stress induced by said edge bearing compressively against the opposite slot wall from said corner substantially by a line contact, the contact line being spaced inwardly of the slot from said one member surface.
